CONSTRUCTION BLOCK

Application filed July 12, 1929. Serial No. 377,717.

This invention relates to blocks used in wall construction, particularly in making conical-shaped walls, for catch basins, cesspools, etc.

For reasons of economy in costs and saving in labor it has been found desirable to make use of blocks made of concrete or cement to build the walls of circular catch basins in place of bricks and other materials which have been used. Since it is practical to make concrete blocks larger than bricks there is the resultant advantage in that a smaller number of blocks are required to build a wall, which means a saving in the labor and mortar required to lay the blocks as compared with bricks, both of which are very expensive items.

It is frequently desirable to build catch basins of the shape of a truncated cone; but in practice this has been found to be difficult and expensive for the reason that in this particular construction the ordinary block having a flat bottom does not rest evenly on the flat top of the block below it. This unevenness is due to the wall being built with an inward pitch, and requires a considerable amount of extra mortar and labor to insert it between the joints than if the blocks set evenly.

One of the objects of my invention is to provide construction blocks at moderate expense of such a shape that the bottoms of the blocks will rest evenly on the top of the blocks immediately below it when building a wall for a catch basin or the like of the shape of a truncated cone. This proved to be very difficult of solution because the top surfaces of the blocks used for the lower or foundation course are made to slant downwardly from the outside to the inside of the catch basin in order to make a conical shaped wall. Using a flat bottomed block was unsatisfactory because of the resulting unevenness previously referred to. The problem presented was not one that could be figured out mathematically; and I was obliged to mould experimental blocks of many different shapes before I was successful in producing one which will rest evenly on the block below

it, so that only the minimum amount of mortar is required to seal the joint.

With the above and other objects in view which will more readily appear as the nature of the invention is better understood, the same consists in the novel construction hereinafter more fully described, claimed and illustrated in the accompanying drawings.

In the drawings:

Figure 1 is a fragmentary elevation of a catch basin of a truncated conical shape partly in cross section, showing my construction blocks as actually used.

Figure 2 is a plan view of one of my construction blocks.

Figure 3 is a side elevation of my block showing it in the position for practical use.

Figure 4 is an end elevation of my block.

Like numerals and letters of reference indicate corresponding parts in each figure.

As illustrated my block B which is usually made of concrete or cement, although any material suited for the purpose may be employed is seven-sided. It consists of a front 12, a back 13, two ends 14, a top 16, two bottom portions 17, the two bottom portions converging outwardly from the opposite ends 14 to form a ridge 19 extending widthwise of the block, at approximately the center. The ends have cut-out portions 20 in the form of a half circle for keying purposes which are well known.

In its preferred shape the ends of my block B are made to slant outwardly from top to bottom, more particularly as shown in Figure 3 of the drawings. In other words the lower portion of my block is longer than the upper portion. This, of course, is to provide for the difference in diameter of the conical catch basin which gradually grows smaller from bottom to top. These ends are also made to slant inwardly from the back 13 to the front 12, or the outside of the wall towards the inside as shown in Figure 2 of the drawings which is a normal characteristic of blocks used to build a circular wall. Of course, the outward slant from top to bottom will vary according to the inward pitch or taper of the wall.

When building a catch basin or cesspool the

shape of a truncated cone as shown in Figure 1 of the drawings the shape of the blocks is of great importance. The blocks forming the lower course which I have designated as 24, 5 have their top surfaces slanted downwardly from the outside towards the inside, to cause an inward pitch of the catch basin. At first thought one might suppose an arcuate block having a flat bottom surface would evenly 10 fit the top surface of the blocks forming said lower course 24. This is not a fact, however, in actual practice, as said block fits very unevenly on the lower course block 24, and considerable extra mortar, as well as labor in inserting the mortar, is required to fill in the 15 space resulting from this unevenness. After many tests I found that by slanting the bottoms of the block outwardly from each end toward the center, so that the thickest point 20 from top to bottom was approximately in the center of the block at the ridge 19, that the bottoms of the block would set evenly on the top surface of said lower course blocks 24. The same holds true as the blocks B are set 25 one upon the other until the wall is completed by the special top block S. As shown in Figure 1 of the drawings, in a catch basin of truncated cone shape the size of the blocks varies, smaller ones being used as the wall is 30 built upwardly, on account of the inside diameter becoming smaller.

This slant of each of the two obliquely disposed faces or bottom portions 17 should be substantially the same from each end 14 toward the ridge 19 although in working with such coarse material as is used in the construction of these blocks a fine accuracy can, not be obtained.

While a specific embodiment of the invention has been illustrated and described, the invention is not to be considered as limited to this specific block, as the angles will be varied in accordance with variations in the size of the block and the inward pitch of 45 the catch basin.

What I claim is:

1. A construction block having a top, ends which slope inwardly from back to front and outwardly from top to bottom, and a bottom 50 having a ridge running widthwise at approximately the center, dividing said bottom into two obliquely disposed portions.

2. In an arcuate construction block the top, front, back and ends having flat surfaces, and 55 the bottom comprising two obliquely disposed faces, each face slanting outwardly from its adjoining end toward the middle, said ends slanting outwardly from front to back and top to bottom.

60 3. A construction block comprising two sides, two ends, a top, and a bottom divided into two portions slanting away from each other.

4. A construction block comprising a flat 65 top, a front, a back, two ends slanting slight-

ly outward from top to bottom and back to front, and a bottom, said bottom being divided by a widthwise ridge at approximately the center of said block into two portions, each of said portions slanting slightly upward 70 from said ridge toward an end.

5. A construction block pentagonal in its shape when viewed in side elevation, having a bottom which is divided into two portions slanting upwardly away from each other, a 75 top and two ends.

6. A construction block so shaped as to have a top, a bottom, a front, a back and two ends, said bottom comprising two portions each slanting outwardly from the adjoining end toward the middle to form a ridge running widthwise of the block. 80

7. A construction block having a top, a bottom, a front, a back and two ends, said bottom comprising two portions pitched outwardly from said ends toward the middle to thereby form a ridge at approximately the center, the plane of the respective ends of the block from top to bottom being at approximately a right angle to the plane of 90 the respective portions of the bottom adjoining said ends.
